SLUG CASTING MACHINE

Anthony J. Stouges, Queens Village, N. Y., assignor to Mergenthaler Linotype Company, a corporation of New York

Application November 30, 1932, Serial No. 644,955

20 Claims. (CL 199—61)

This invention relates to slug casting machines, wherein matrices are composed in line, the composed line presented to the face of a mold, and the mold filled with molten metal to form a slug against the matrices which produce the type characters thereon. As the slugs are successively cast, they are ejected from the mold and discharged into a receiving galley, wherein they are assembled side by side in a row or column under the influence of a periodically operated stacking device. Such a machine is illustrated in U. S. Letters Patent to O. Mergenthaler, No. 436,532.

In machines of this character, it is customary to permit the slugs as they are received in the galley to cool merely by exposure to the atmosphere, but when a slug of particularly large face is cast, cooling is necessarily slow due to the large mass of metal contained in the slug.

In accordance with this invention, the slug is cooled quickly by subjecting it to the action of a cooling medium after it has been ejected from the mold. The cooling preferably is effected in the galley, and for this purpose the base plate of the galley is provided with a series of apertures above which the slug is brought to rest as it is received from the casting mold. The cooling medium is ejected through these apertures directly against the slug, and thereafter the slug is advanced in the galley to make room for the next slug.

Although a different fluid cooling medium may be employed in practicing the invention, water is preferred, since it is the easiest to handle and most desirable for the purpose. Hence, a reservoir for water is provided together with a pump which has a connection with the apertures in the galley base plate. The pump is operated from the main cam shaft of the machine, so as to insure its operation in timed relation to the delivery of the slug to the galley and the operation of the stacking mechanism. A drain connects the galley with the reservoir to return the cooling fluid thereto after the slug has been cooled.

As the invention is concerned chiefly with the casting of slugs of the recessed variety, the apertures in the galley base plate are so arranged that the fluid will be projected into the recesses of the slugs provided between the usual spaced transverse supporting ribs integrally formed on the body beneath the character bearing portion. In this way, the maximum amount of slug surface is exposed to the action of the cooling medium.

In the accompanying drawings:

Fig. 1 is a partial vertical section through a

Fig. 2 is a plan view of a galley showing it equipped with the cooling apparatus and the means for operating the slug stacker; and

Fig. 3 is a front elevational view, partly in section, showing the slug stacker and a portion of the cooling mechanism.

In the description to follow, reference will be made to well known parts of the casting mechanism of a slug casting machine which form no part of the present invention, and for this reason only those parts necessary to a complete understanding of the invention have been illustrated in the accompanying drawings. However, a detailed description of these parts and their mode of operation can be found in the Mergenthaler patent already referred to.

As usual, the slugs S are cast in a slotted mold B carried by a disc B' which is rotatably mounted on a mold slide so as to locate the mold first in a horizontal position for casting and then in a vertical position for the ejection of the cast slug. During the casting operation, the mold is closed at the front by a composed line of matrices presented thereto by the first elevator or line transporter indicated generally by the letter A arranged to reciprocate in the customary guideways of the vise frame A'. The ejection of the cast slug is effected by an ejector blade B² operated from the main cam shaft M and which advances from the rear and pushes the slug forwardly through a pair of trimming knives mounted on the vise frame A' in alignment with the mold when the latter is in its ejecting position, whereafter the slug falls by gravity into a chute B³, which delivers it to an inclined galley C suitably mounted at the front of the machine on brackets C' secured to the vise frame A'. During the subsequent operation of the machine, a stacking mechanism D is operated to advance the slug in the galley toward the left out of the path of the slug next to be delivered.

The slugs S (shown in the accompanying drawings and in connection with which the present invention is particularly concerned) are of the ordinary recessed variety, being L-shaped in cross section and comprising a relatively thin body portion S' and an overhanging character bearing portion S² supported by a series of spaced transverse ribs S³ formed integrally on the body and underneath the character bearing portion.

So far as described, the parts and their mode of operation, except as hereinafter pointed out,

are or may be the same as those embodied in the commercial linotype machines, or as disclosed in the Mergenthaler patent before referred to.

5 The galley C to which the slugs are delivered is inclined in the usual manner, but in accordance with this invention that portion of its base plate C² in line with the discharge end of the chute B³ is provided with a series of apertures C³ through 10 which a cooling medium, such as water, is adapted to be ejected. The cooling fluid is contained in a reservoir R suitably mounted at the rear of the supporting frame F.

15 Within the reservoir is a pump unit P having a cylinder formed integrally with the base of the reservoir, and within the cylinder is a pump piston P' reciprocable upwardly and downwardly. Adjacent the lower end of the cylinder is a fluid outlet P² which is connected with the apertures in the base plate of the galley by a 20 pipe P³ supported by a hanger member F' carried by the frame F of the machine.

25 When the piston is in its upper position, as shown by the solid lines in Fig. 1, communication is provided from the reservoir to the interior of the pump cylinder by a plurality of apertures P⁴ arranged just below the piston in this position. The fluid flows through these apertures to fill the pump cylinder, and upon the 30 downward stroke of the piston to the position shown by the dotted lines in Fig. 1, the fluid is forced through the pipe P³ to the galley C, where it is caused to impinge upon the slug S.

35 Means are provided for regulating the volume of fluid delivered to the galley so as to prevent undue splashing and overflow. Such means comprises a recess P⁵ formed in the bottom of the pump piston and which communicates with the space above the piston through an aperture P⁶ formed in the wall of the recess. The effective 40 opening of the aperture is adjustable by means of a screw P⁷ threaded into the upper wall of the recess adjacent the aperture, so that by varying the adjustment of the screw, the volume 45 of liquid permitted to flow to the top of the piston upon each stroke thereof may be varied. Thus, if a large flow of fluid to the galley is desired, the screw is adjusted for a small back flow, whereas for a small flow of fluid to the 50 galley an adjustment giving a large back flow is made.

55 The piston P' preferably is operated from the main cam shaft M of the machine in order properly to time the ejection of fluid into the galley just prior to or co-incidental with the delivery 60 of the slug thereto. A cam M' is keyed to the shaft and coacts with an underlying bent lever M² pivoted at its rear end to the machine frame and held in contact with the cam by a spring M³ connected between the forward end of the 65 lever and the machine frame. The motion of the lever is transmitted to the pump piston by a connecting link M⁴, pivoted at its upper end intermediate the ends of the lever and at its lower end to the top of the piston P'. The cam 70 rides upon a bearing member M⁵ provided at the upper edge of the lever M², and when the cam shaft rotates to bring the high portion of the cam into contact with the lever, the piston is pushed downwardly, forcing the cooling fluid to the galley where it is ejected against a slug 75 which substantially at this instant is delivered to the galley. Upon further rotation of the shaft, to bring the low portion of the cam into contact with the bearing member on the lever, the pump piston is drawn upwardly under the

influence of the spring M³, which always maintains the lever in contact with the cam, the latter consequently determining the speed of operation of the pump.

80 As mentioned heretofore, the galley C is mounted at the front of the machine on brackets C' connected to the vise frame A'. The galley comprises a plate C² suitably secured to the brackets as by screws, and having the apertures C³, as heretofore mentioned, arranged at the right in line with the discharge end of the chute B³, from which the slugs are delivered. Underlying the plate C² and fastened thereto by screws is a casting C⁴ having a chamber C⁵ connecting the apertures with the pipe P³ leading from the pump. The upper or outlet portion of the chamber encompasses all of the apertures and its lower or inlet portion terminates in a nipple over which the end of the fluid pipe connection fits and to which it is fastened by a suitable clamp.

85 90 95 After the fluid has cooled the slugs, it is drained from the galley and delivered back to the reservoir. For this purpose, the galley is provided in its front and lowermost portion with a drain hole C⁶ cut through the plate C², and which communicates with another chamber C⁷ in the casting C⁴ underlying the plate. This chamber C⁷ tapers downwardly, terminating in a nipple to which a second pipe C⁸ is connected by a suitable clamp, the pipe leading from the galley to the fluid reservoir R. This pipe also is supported by the hanger member F' and has its outlet end terminating adjacent the top of the reservoir R, so that the fluid may flow back into the reservoir for use over again. C⁴. The rod is movable inwardly or to the left in the galley to cause the stacker to push the slug from the position shown by the full lines in Fig. 3 to that indicated by the dotted lines therein. The 5 rod is connected at its outer end to the upper end of an offset lever D⁴ which in turn is pivoted at its lower end to a horizontal extension D⁵ of the galley support bracket C'. The movement of the lever D⁴ is controlled from a cam A² mounted 10 upon the first elevator slide A. The edge of the cam extends vertically for a distance and then slopes upwardly to the left or in the direction in which the slugs are moved during the stacking operation. The control is effected through a movable rod D⁶ slidably supported in a sleeve D⁷ in the galley support bracket C'. One end of the rod is equipped with a shoe D⁸ adapted to slide upon the edge of the cam A², and the other end with a bearing plate D⁹ upon which bears an 15 anti-friction roller D¹⁰ carried by the lever D⁴ and spaced somewhat above its lower pivot point. A spring D¹¹ is connected between the lever and a galley support bracket and serves to urge the shoe against the cam edge. 20 As a result of the foregoing construction, when the first elevator or line transporter is moved downwardly prior to casting, the lever D⁴ is rocked to the left under the influence of the spring D¹¹, when the sloping upper portion of the cam A² 25 passes the shoe D⁸, to advance the slug in the galley out of the way of the slug next to be delivered. Upon the upward movement of the elevator after casting, the cam A² actuates the rod D⁶ to the right, rocking the lever D⁴ against the 30 tension of the spring D¹¹ and returning the stacker D' to normal position.

As stated at the outset, the cooling attachment is particularly useful in connection with casting large slugs, that is those of the recessed variety, 40 having an L-shaped cross section with a plurality of spaced transverse ribs integrally formed on the body of the slug and underneath the character bearing portion. In order to expose the greatest surface possible to the action of the 45 cooling medium, the apertures C³ in the base plate of the galley are preferably spaced in pairs so that each pair is positioned between two spaced transverse ribs. In this way, a maximum amount of the slug surface will be exposed to the cooling 50 medium, and as the stacker bar is immediately adjacent one of the open faces of the slug, the cooling medium is projected into substantially closed recesses formed by the inner face of the slug body and character bearing portion, two 55 transverse ribs and the face of the stacker bar. The result of this is to confine the cooling fluid and reduce splashing.

Although it is believed the invention is fully understandable from the foregoing description, a 60 brief review of the operation may be helpful. After a slug is cast in the mold B, the disc B' is rotated to locate the mold in the ejecting position, and the slug is then ejected into the chute B³ by operation of the ejector B², whence it is 65 delivered to the galley C where it is brought to rest, upon striking the bumper C¹², in a position immediately over the aperture C³ in the base plate of the galley and adjacent the stacker D' in its retracted position. Substantially co-incident 70 with the delivery of the slug, the pump operating cam M' on the cam shaft causes the downward movement of the pump piston P' which forces the cooling fluid through the connecting pipe P³ to the apertures C³ in the galley base plate 75 where it is ejected against the slug. After effect-

ing the cooling of the slug, the water is drained from the front of the galley back through the return pipe C⁸ to the reservoir R.

When the elevator slide A is lowered for the casting of the next slug, the sloping portion of the cam A² on the elevator slide A passes below the shoe D⁸ on the rod D⁶ controlling the lever D⁴, to which the slug stacker is connected. The lever D⁴ is thus rocked to the left under the influence of the spring D¹¹, pushing the stacker to the left to move the previously cast slug out of the way to make room for the slug presently to be delivered. Upon the upward movement of the elevator slide, the stacker bar is returned to normal position in the manner heretofore described preparatory to stacking the next slug.

It may be explained that the action of the pump unit is such that the water is caused to pass quite slowly through the apertures C³, issuing in the form of small jets under low pressure. Due to the large number of apertures, however, and to the obstruction offered by the slug itself, the water will accumulate more rapidly than it is carried off, so that for a brief period the slug will be partly submerged in a pool of water. This will of course aid in the cooling of the slug. Indeed, so rapid is the cooling of the slug that it may be picked up with the bare hand immediately after casting, as is frequently desired in the case of the larger slugs.

In the accompanying drawings the invention has been shown merely in preferred form and by way of example, but it will be understood that many changes and modifications may be made therein and in its mode of application without departing from the spirit of the invention. It is to be understood, therefore, that the invention is not limited to any specific form or arrangement, except insofar as such limitations are specified in the appended claims.

Having thus described my invention, what I claim is:

1. In a slug casting machine, the combination of a mold in which a slug is cast, means for ejecting the slug from the mold, and means actuated in timed relation to the slug ejecting means for subjecting the slug to the action of a cooling medium after ejection.

2. In a slug casting machine, the combination of a mold in which a slug is cast, means for ejecting the slug from the mold, a galley for receiving the slug, and means for subjecting the slug while at rest in the galley to the action of a cooling medium.

3. In a slug casting machine, the combination of a mold in which a slug is cast, means for ejecting the slug from the mold, and means for spraying water on the ejected slug.

4. In a slug casting machine, the combination of a mold in which a slug is cast, means for ejecting the slug from the mold, a galley for receiving the slug, stacking mechanism for advancing the slug in the galley prior to the delivery of a subsequently cast slug, and means for subjecting the slug in the galley to the action of a cooling medium prior to the operation of the stacking mechanism.

5. In a slug casting machine, the combination of a mold in which a slug is cast, a transporter for presenting a composed line of matrices to the mold during the casting of the slug, means for ejecting the slug from the mold, a galley for receiving the slug, stacking mechanism operated by said line transporter to advance the slug in the galley prior to the delivery of a subsequently

cast slug, and means for subjecting the slug in the galley to the action of a cooling medium prior to the operation of the stacking mechanism.

6. In a slug casting mechanism, the combination of a mold in which a slug is cast, a transporter for presenting a composed line of matrices to the mold during the casting of the slug, a galley for receiving the slug, means for subjecting the slug to the action of a cooling medium in the galley, and stacking mechanism acting during a subsequent slug casting cycle of operation to advance the cooled slug in the galley.

7. In a slug casting machine, the combination of a mold in which a slug is cast, a transporter for presenting a composed line of matrices to the mold during the casting of the slug, means for ejecting the slug from the mold, a galley for receiving the slug, a cam carried by said line transporter, a stacking mechanism operated by said transporter cam to advance the slug in the galley prior to receiving a subsequently cast slug, and means for subjecting the slug to the action of a cooling medium prior to the operation of the stacking mechanism.

8. In a slug casting machine, the combination of means for delivering a cast slug from the machine, and means for directing a cooling fluid against said slug.

9. In a slug casting machine, the combination of means for receiving a cast slug after ejection from the machine, and means for circulating a cooling fluid through said receiving means to cool the slug.

10. In a slug casting machine, the combination of a galley for receiving a cast slug after ejection from the machine, a plurality of apertures arranged in the base of the galley in the vicinity where the slug is received, and means for directing a cooling fluid through said apertures and against the slug.

11. In a slug casting machine, the combination of a galley for receiving a cast slug after ejection from the machine, a plurality of apertures arranged in the base of the galley in the vicinity where the slug is received, means for directing a cooling liquid through said apertures and against the slug, and means for draining the liquid from the galley.

12. In a slug casting machine, the combination of a galley for receiving a cast slug after ejection from the machine, a series of apertures in the base of the galley, a reservoir containing a cooling liquid, a pump, and means for operating the pump, said pump acting to force liquid through said apertures and against the slug.

13. In a slug casting machine, the combination of a galley for receiving a cast slug after ejection from the machine, a series of apertures in the base of the galley, a reservoir containing a cooling liquid, a pump, means for operating the pump, said pump acting to force liquid through said apertures and against the slug, and means for draining the liquid from the galley and returning it to the reservoir.

14. In a slug casting machine, the combination of a mold in which a slug is cast, means for ejecting the slug from the mold, a main drive shaft, means mounted on said shaft for operat-

ing the slug ejecting means, a galley for receiving the slug, a series of apertures in the base of the galley, a reservoir containing a cooling liquid, a pump, means also mounted on said main shaft for operating the pump, a pipe connecting said pump with said apertures whereby liquid from the pump is forced through the apertures and directed against the slug, and means comprising a pipe draining the liquid from the galley back to the reservoir.

15. In a slug casting machine, the combination of a mold in which a slug is cast, means for ejecting the slug from the mold, a main drive shaft, a cam mounted on said shaft for controlling said ejecting means, a galley for receiving the ejected slug, stacking mechanism for advancing the slug in the galley prior to receiving a subsequently cast slug, a series of apertures in the base of the galley, a reservoir containing a cooling liquid, a pump, a pipe connecting the apertures with the pump, means comprising a cam also mounted on said main shaft for operating the pump to force liquid from the reservoir through the apertures and into contact with the slug in the galley, and means for returning the liquid from the galley to the reservoir.

16. In a slug casting machine, the combination of a mold adapted to cast a slug with a plurality of spaced supporting ribs underlying the face thereof, means for ejecting the slug from the mold, a galley for receiving the ejected slug, a series of apertures arranged in the base of the galley, and means for ejecting a cooling fluid through said apertures and against the slug, said apertures being so arranged and spaced, that the cooling fluid is directed against the slug in the recesses formed by the supporting ribs.

17. In a slug casting machine, the combination of a mold adapted to cast a slug with a plurality of spaced supporting ribs underlying the face thereof, means for ejecting the slug from the mold, a galley for receiving the ejected slug, a slug stacker arranged at one end of the galley, a series of apertures in the base of the galley adjacent the slug stacker, and means for projecting a cooling fluid through said apertures and against the slug, the slug and stacker together forming a plurality of enclosures for confining the cooling fluid.

18. A cooling device for use with a slug casting machine, comprising a holder for receiving a slug ejected from the machine, and means associated with the holder for directing a cooling medium against the slug while it is at rest in the holder.

19. A cooling device for use with a slug casting machine, comprising a holder for receiving a slug ejected from the machine, and means associated with the holder for providing a cooling medium for the slug while it is at rest in the holder.

20. A cooling device for use with a slug casting machine comprising a holder for receiving a slug ejected from the machine, means for projecting liquid into said holder for cooling the slug while it is at rest in the holder, and a drain for disposing of the liquid.

ANTHONY J. STOUGES.
